DESIGN FOR A PICTURE MOUNT

Harold F. Moonert, Willoughby, Ohio

Application March 8, 1945, Serial No. 118,346

Term of patent 3½ years

(Cl. D29—20)

To all whom it may concern:

Be it known that I, Harold F. Moonert, a citizen of the United States of America, residing at Willoughby, in the county of Lake and State of Ohio, have invented a new, original and ornamental Design for a Picture Mount, of which the following is a specification, reference being had to the accompanying drawing, forming part thereof.

In the drawing:

I claim:

The ornamental design for a picture mount, as shown.

HAROLD F. MOONERT.
